UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

DRAFT KEY RETAINER

Application filed December 3, 1925. Serial No. 72,969.

This invention relates to retaining devices and, more particularly, to such especially adapted for application to draft keys for preventing loss or undesired removal thereof.

5 The principal object of my invention, generally considered, is the provision of an improved retainer or locking device particularly adapted for application at one or both ends of draft rigging keys at reduced sections thereof for effectively and conveniently preventing undesired removal or loss of said keys.

An object of my invention is the provision of a U-shaped retainer adapted for being seated on one or both ends of draft keys at reduced sections thereof, said retainer being formed with depending arms engaging the key at such reduced section with a portion of reduced width connecting said arms.

20 Another object of my invention is the provision of a retainer adapted for embracing an associated draft key at a portion of reduced width thereon, said retainer being formed with depending arms of greater width than the rest of the device whereby they provide spaced portions for engagement with the adjacent cheek plate or draft sill of the car, said portions extending beyond the opposite surface of the associated key and being joined by removable fastening means.

A further object of my invention is the provision of an integral inverted U-shaped draft key retainer adapted for application at an end of an associated draft key with depending arms extending into slots or notches in the opposite side edges of said key, the lower ends of said arms extending below the bottom of the key and formed with apertures therein for receiving a removable locking bar or cotter.

40 Other objects and advantages of the invention relating to the particular arrangement and combination of the various parts will become apparent as the description proceeds.

Referring to the drawings illustrating my invention, the scope whereof is defined by the appended claims:

50 Figure 1 is a side elevation of a draft rigging and a portion of a car underframe to

which said draft rigging is applied showing draft rigging keys with retaining devices thereon embodying the principles of my invention.

Figure 2 is a top plan view showing the 55 end of a draft key with a retaining device embodying the features of my invention applied thereon, a portion of an associated cheek plate being also illustrated.

Figure 3 is an elevational view shown partly in section on the line 3—3 of Figure 2.

Figure 4 is an end elevational view shown partly in section on the line 4—4 of Figure 2.

Although my invention is applicable to draft keys generally and may be used with 65 various kinds of draft rigging, I have, for illustrative purposes, shown in Figure 1 my invention employed with draft rigging of the Farlow two-key type. In Figure 1, a fragmentary portion of a car underframe is illustrated and draft or center sills 1 are shown with cheek plates 2 applied on the outer sides of the webs 3 thereof, in accordance with usual practice. Said cheek plates 2 are connected to the sills by rivets 4 and are formed 70 with flange portions 5 defining slots 6 and 7 therethrough. Through the slots 6 and 7 extend draft keys 8 and 9, respectively, and said keys serve for connecting and supporting an associated coupler 10, yoke 11, and 80 front follower 12. Cooperating with said follower 12 and embraced between the arms of the horizontal yoke 11 illustrated is a cushioning mechanism illustrated diagrammatically by dot and dash lines. 85

The keys 8 and 9 or one of them are formed adjacent one or both ends thereof or intermediate said ends with a portion 13 of reduced cross section. The portion 13 may be conveniently formed by cutting notches or 90 slots 14 in the opposite side edges thereof, as illustrated particularly in Figure 2, although, if desired, the portion of reduced cross section may be formed in some other manner, for example, by grooving or slotting other portions of the key or by heading or upsetting the end portions or an end portion thereof. The retaining device 15 is applied to said key preferably, as illustrated in the drawings, so that it completely embraces the same at the 100

reduced section 13 thereof. If used on only one end of a key, the other end may be headed or of any usual or desired construction.

The retaining device 15 preferably comprises an integral inverted U-shaped member 16 which may be conveniently formed by casting, said member 16 comprising depending arms 17 connected by a portion 18 preferably formed of reduced width. That is, the arms 17 of the U-shaped member 16 are preferably wider than the connecting portion 18 so that they engage with the adjacent flange 5 of the cheek plate 2 or with the web 3 of the draft or center sill 1, if exterior cheek plates are not employed, thereby receiving substantially all the strain between the key and cheek plate and relieving the connecting portion 18 of substantially all working strain. On account of such construction, the connecting portion 18 may be formed relatively light in weight and may be further lightened by forming the same with a rib 19 extending between the depending arms 17 and being relatively strong or deep at the central or intermediate portion thereof and merging at its ends into the arms 17.

If the device 16 is formed by casting, the inner corners between the depending arms 17 and the connecting portion 18 are preferably relieved or filleted as indicated at 20, so that the lower surface of the inverted U-shaped portion 16 will seat on the upper surface of the associated key at the reduced section 13 thereof without interference at the corners.

The lower ends of the depending arms 17 preferably extend below or beyond the opposite surface or side of the key to that on which the connecting portion 18 seats and are connected by detachable connecting means 21. Said connecting means 21 conveniently takes the form of a bar, one end 22 of which is initially bent, as illustrated, and serves as the head thereof, the other end being insertable through registering apertures 23 adjacent the lower ends of the depending arms 17. When the U-shaped member 16 is seated on the key, as illustrated, and the retaining bar 21 inserted in place, the straight end 24 thereof may be bent from the position indicated by dot and dash lines to that shown in full lines for removably retaining the device 15 in place. When it is desired to remove the device, the end 24 of the rod may be readily straightened so that the same may be removed to allow the U-shaped member 16 to be completely detached from the associated key.

From the foregoing disclosure, it will be apparent that I have devised a new retaining means particularly adapted for draft keys although, as is obvious, it is suitable for other purposes. Although the U-shaped member is shown applied upon the top surface of the key, it is obvious that I do not wish to be

restricted to such a showing as, if desired, it may be applied from below with the retaining means 21 above the same. Also I do not wish to be restricted to the precise construction of the reduced section 13 on the draft key as said section may be formed in any desired way and the retaining device 15 altered in construction accordingly. Although the connecting portion 18 is preferably narrower than the depending arms 17, yet I do not wish to be restricted to such a showing as it may be deemed advisable to form the same of a corresponding width or of such a width that it will engage the adjacent portion or flange of the associated cheek plate and provide an increased bearing area therebetween.

Having now described my invention, what I claim is:

1. In combination, a flat draft key elongated in cross section and having intermediate its ends a portion of reduced cross section, and retaining means embracing said key at said portion of reduced section, said means comprising a member with an intermediate portion seated on the key, depending arms wider than said intermediate portion in the direction of the axis of the key, and rigidified by a rib extending from end to end along the upper face thereof and detachable means extending between the free ends of said arms on the other side of said key.

2. In combination with a railway vehicle underframe, a draft key elongated in cross section and having a portion of reduced cross section intermediate its ends and retaining means embracing said key at said portion, said means comprising a member formed with spaced arms, the sides only of which are adapted to engage the adjacent portions of the underframe, connected by a portion of reduced width and being seated on said key with detachable means extending between the free ends of said arms on the opposite side of the key from the portion of reduced width, said connecting portion being of maximum depth adjacent to center and tapering in depth toward each end.

3. In combination, a draft key having intermediate its ends shouldered portions formed in opposite side edges of said key, and retaining means embracing said key, said means comprising an integral inverted U-shaped member with arms of relatively great width engaging said shouldered portions, the connecting portion between said arms being relatively narrow and formed with a rib therealong increasing in strength towards its central portion, said arms extending beyond the opposite side of the key and being connected by detachable means extending therebetween.

4. In combination, a draft key elongated in cross section and formed with notches or slots adjacent one end thereof, and retaining

means extending into said notches and embracing said key, said means comprising an inverted U-shaped member formed with depending arms extending into and of a width greater than the intermediate portion so as to fill said notches and continued below the bottom surface of the key, that portion of said U-shaped member between said arms being reinforced by an outstanding rib, apertures formed in the portions of the arms below said key and detachable means extending through said apertures for preventing undesired removal of said retaining means.

5. A draft key retaining device comprising a relatively narrow intermediate portion rigidified by a tapering rib and adapted to seat on a flat key and depending end portions enlarged axially of the key and adapted to fit in notches therein at a reduced section thereof and apertured for receiving detachable fastening means.

6. A retaining device adapted for embracing a flat draft key at a notched section thereof comprising an inverted U-shaped member with a straight intermediate portion reinforced by an upstanding flange and adapted to seat on the flat top of said key and depending arms for completely closing the notches, the lower ends of said arms being adapted for connection by a detachable member serving to prevent undesired removal of the device when in place.

7. A retaining device comprising an integral inverted U-shaped member formed with depending arms of relatively great width, a connecting portion between said arms of reduced width and a tapering rib extending along said connecting portion for strengthening the same, said rib being relatively strong at its central portion and merging at its ends into the depending arms, the lower ends of said arms being adapted for temporary connection for holding the device in place.

8. A retaining device comprising an inverted U-shaped member with a straight intermediate portion reinforced by a tapering rib and adapted to seat on a flat draft key and arms adapted to embrace said key at a portion of reduced section and formed of increased dimension axially of said key, said arms being adapted to extend beyond the opposite surface of the associated key and formed with perforations adjacent said surface and a retaining member adapted for insertion through said perforations for preventing undesired removal of the device.

In testimony whereof I affix my signature.
DONALD S. BARROWS.
